TOY

Filed Feb. 17, 1932

UNITED STATES PATENT OFFICE

ALFRED B. RODE, OF NEW YORK, N. Y., ASSIGNOR TO RODE & BRAND, OF NEW YORK,
N. Y., A CORPORATION OF NEW YORK

TOY

Application filed February 17, 1932. Serial No. 593,484.

This invention relates to improvements in toys and has for its particular object the provision of a novel form of toy for producing smoke rings.

5 A particular object of this invention is the provision of a novel form of toy for producing smoke rings which can be economically manufactured and which is collapsible.

10 Further objects of this invention will be apparent from the specification and drawing, in which Fig. 1 is a perspective view showing the device in operation.

Fig. 2 is a sectional view of the device 15 along the line 2—2 of Fig. 1.

Fig. 3 is a front elevation showing part of the mouthpiece partially detached.

20 10 indicates the box in which the smoke rings are produced, 11 the front or mouthpiece portion, 12 being the mouthpiece itself.

25 13 indicates the opening through which the smoke rings emerge; 14 are tabs attached to the mouthpiece portion of the device engaging in the slots 15. 16 is the turned-up flange of the mouthpiece portion which is preferably glued or cemented to the frame of the box 10.

The frame of the box 10 is preferably made 30 from a single sheet of cardboard properly scored and folded so as to make an approximately cubical container, to the front portion of which is attached the conical member 11, having the mouthpiece 12.

The member 11 is preferably also made 35 from a single sheet of cardboard properly scored and folded.

H indicates the hand of the operator and R the smoke rings themselves.

40 After introducing smoke through the lips into the opening 13, the rings are produced by gently tapping with the fingers on the rear of the box 10 as shown in Fig. 1 of the drawing. With a little practice, perfect rings in large quantity can be easily produced by 45 this device.

I have discovered that in order to make this device properly operative, the rear wall 50 17 of the box into which the smoke is led must not be hermetically attached to the contiguous walls of the box, but that there must

be openings adjacent the edges of the rear wall 17 so as to permit air to enter into the box when blows are struck by the hand upon the wall 17 as illustrated in Fig. 1.

For this reason the wall 17 folds inwardly 55 by means of the flange 18 onto the bottom of the box 19, leaving the opening 20 for the admission of air.

I have found by experiment that when the rear wall of the box is closely sealed to 60 the contiguous walls so that no air can be admitted into same when the wall 17 is struck, that in this event no smoke rings are produced even if smoke is introduced into the box 10, and the device operated in the usual 65 manner.

It is apparent that further changes in the device may be made without departing from the spirit of my invention.

Having fully described my invention, what 70 I claim is:

1. A toy device for producing smoke rings, a cubical box, serving as a smoke container, an opening in the front of said box, a conical member attached to the front of said box by 75 means of a plurality of flaps on said member, which flaps engage corresponding slots in said box, one or more flaps on said member turned over to rest on the outer front surface of said box, a circular hole in the front of said conical member, a slightly movable rear wall on said box and air openings adjacent the edges of the rear wall for the proper operation of the toy device for producing smoke rings. 80

2. A toy device for producing smoke rings, a cubical box, serving as a smoke container, an opening in the front of said box, a conical member attached to the front of said box by 90 means of a plurality of flaps on said member, which flaps engage corresponding slots in said box, one or more flaps on said member turned over to rest on the outer front surface of said box, a circular hole in the front of said conical member, a slightly movable rear wall on said box, a flange at the lower end of said wall, folded inwardly to rest on the bottom of the box to guide said rear wall and cause 95 the same to bend so as to form air openings 100

adjacent the edges of the rear wall for the proper functioning of the toy device.

3. A toy device for producing smoke rings, a cubical box serving as a smoke container, a circular opening in the front wall of said box, a mouth piece which forms a frustum of a pyramid attached to the front wall of said box by means of a plurality of flaps on said mouthpiece, which engage corresponding slots in said box, one or more flaps on said member turned over to rest on the outer front surface of said box, a circular hole in the front of said mouth piece, a slightly movable rear wall on said box and air openings adjacent the edges of the rear wall for the proper operation of the toy device for producing smoke rings.

4. A toy device for producing smoke rings, a cubical box serving as a smoke container, a circular opening in the front wall of said box, a mouth piece which forms a frustum of a pyramid attached to the front wall of said box by means of a plurality of flaps on said mouth piece, which engage corresponding slots in said box, one or more flaps on said member turned over to rest on the outer front surface of said box, a circular hole in the front of said mouth piece, a movable rear wall on said box, a flange at the lower end of said wall, folded inwardly to rest on the bottom of the box to guide said rear wall and cause the same to bend so as to form air openings adjacent the edges of the rear wall for the proper operation of the toy device to produce smoke rings when tapped on the rear wall thereof.

In testimony whereof I affix my signature.
ALFRED B. RODE.
